UNITED STATES PATENT OFFICE.

MAX GALKE, OF EISENACH, GERMANY.

CROSSWISE-REINFORCED-CONCRETE RIBBED CEILING WITH HOLLOW OR LIGHT BLOCKS.

Application filed February 7, 1925. Serial No. 7,673.

To all whom it may concern:

Be it known that I, MAX GALKE, a citizen of the German Republic, residing at Eisenach, Germany, have invented certain new and useful Improvements in Crosswise-Reinforced-Concrete Ribbed Ceilings with Hollow or Light Blocks, for which I have filed an application in Germany, July 14, 1923, of which the following is a specification.

The reenforced concrete ribbed ceiling formed by hollow blocks or light blocks is, according to the present invention, reenforced crosswise by special filling bodies (bricks) of convenient building material, of square, rectangular or other shape which have upper projections approximately of the height of the compression girder or beam and spaced in such a manner that the concrete filling in the intervals and between the ribs produces a continuous lattice-work compression girder possessing the desired compressive strength or bending strength without taking in consideration the projections. The continuous cavities, arranged in the upper surfaces of the filling bodies which together with the concrete filling form the lattice-work compressing girder are in this case a substitute for the continuous concrete layer which has hitherto been arranged over the entire surface of the ceiling.

An embodiment of the invention is shown, by way of example, on the accompanying drawing, in which:—

Fig. 1 is a longitudinal section through the improved ribbed ceiling on line A—B of Fig. 2.

Fig. 2 is a plan view of the ceiling.

Fig. 3 shows on enlarged scale two filling bodies according to the invention limited by stress ribs, in section on line C—D of Fig. 4.

Fig. 4 shows on enlarged scale a plan view of a filling body.

The ceiling is produced without sheeting upon poling boards 1 placed accurately horizontally. Upon the poling boards 1 the plates 2 are placed at such distances apart from one another that the longitudinal stress ribs 5 and the transverse stress ribs 6 required for the reception of the statically calculated iron insertions 3, 4 are obtained.

For the production of the transverse stress ribs 6 short laths 7 are nailed on the poling boards 1 and boards 8 are placed on these

laths as moulds for the transverse stress ribs. The poling boards 1 may be eventually supported by girders 9 (Fig. 1).

The cavities 10 arranged in the upper surfaces of the bricks or filling bodies 2 are the essential feature of the invention, a trellis work compression girder being formed by ramming or centring gravel concrete into said cavities. Owing to the formation of this lattice work compression girder by ramming or centring gravel concrete into the continuous cavities the continuous layer of concrete which, according to the building regulations, have to be used for all ceilings of light concrete possessing low resisting capability, is no longer necessary. The projections 11 formed by the net-like cavities 10 must be of such dimensions and they must be spaced in such a manner that the lattice work concrete layer preserves the required static effect as compression girder of the ceiling.

By the arrangement of these ribbed compression girders 12, formed by the cavities having rounded corners 13, the prescribed concrete compression girder is practically situated on the surface of the ceiling.

The ribbed compression girders 12 have preferably arches 14 similar to bridge girders the sides of which are inclined towards the stress ribs 5, 6 (Figs. 1 and 3).

The load capability of this ceiling is very great as the ribbed compression girders are made at the same time as the cross- and longitudinal stress ribs 5, 6 so that the supporting parts are rigidly connected with one another and the ribs are solidly connected with the projections 11 of the bricks and consequently strengthened.

The stress ribs 5, 6 are preferably enlarged at the lower ends up to $\frac{1}{3}$ of their height (Fig. 3) in order to form an abutment for the four corners of each brick 2.

By the lattice work like arrangement of the ribbed compression girders 12 about $\frac{2}{3}$ of the usual continuous concrete layer of at least 4 to 5 cms. thickness is economized. It is not to be overlooked that these concrete layers subsequently brought onto the ceiling have practically no intimate connection with the ceiling proper.

Besides the economy of $\frac{2}{3}$ of the concrete material the casting and planishing of the ceiling are very simple as the surfaces of the projections 11 of the stones serve as a gauge.

The improved ceiling presents the following advantages:—

1. Transferring of the statically required continuous concrete layer onto the surface of the ceiling owing to the arrangement of the lattice work like ribbed compression girders 12.
2. Nailability of the parts of the stones for ceiling made from light concrete which reach up to the upper surface of the ceiling and remain standing. The wooden beams for the floor which are commonly required are therefore no longer necessary as it is sufficient to nail the thin laths on which the floor boards are nailed. The thickness of the ceiling is also reduced.

I claim:—

1. A crosswise reenforced concrete ribbed ceiling comprising in combination light filling bodies spaced to form continuous longitudinal and transverse intervals between the filling bodies, said intervals standing at right angles to one another, projections on the upper surface of said filling bodies, said projections having approximately the height of a commonly used compression girder and being spaced at regular intervals, reinforcing rods in the longitudinal and transverse intervals between said filling bodies, and a concrete filling of the intervals both between said filling bodies to form longitudinal and transverse stress ribs and between said projections of the filling bodies to form a continuous lattice work like compression girder of desired compressive or tensile strength situated in the surface of the ceiling.
2. A crosswise reenforced concrete ribbed ceiling comprising in combination light filling bodies having each a curved upper surface and spaced to form continuous longitudinal and transverse intervals between the filling bodies, said intervals standing at right angles to one another, projections on

the upper surface of said filling bodies, said projections having approximately the height of a commonly used compression girder and being spaced at regular intervals, reinforcing rods in the longitudinal and transverse intervals between said filling bodies, and a concrete filling of the intervals both between said filling bodies to form longitudinal and transverse stress ribs and between said projections of the filling bodies to form a continuous lattice work like compression girder of desired compressive or tensile strength situated in the surface of the ceiling and having vaulted arch like lower surfaces between and inclined towards said stress ribs.

3. A crosswise reenforced concrete ribbed ceiling comprising in combination light filling bodies having each a curved upper surface and inwardly inclined side walls and spaced to form continuous longitudinal and transverse intervals between the filling bodies, said intervals standing at right angles to one another, projections on the upper surface of said filling bodies, said projections having approximately the height of a commonly used compression girder and being spaced at regular intervals, reinforcing rods in the longitudinal and transverse intervals between said filling bodies, and a concrete filling of the intervals both between said filling bodies to form longitudinal and transverse stress ribs enlarged in the lower part to serve as abutments for the four corners of said filling bodies and between said projections of the filling bodies to form a continuous lattice work like compression girder of desired compressive- or tensile strength situated in the surface of the ceiling and having vaulted arch like lower surfaces between and inclined toward said stress ribs.

In testimony whereof I affix my signature.

MAX GALKE.
